UNITED STATES PATENT OFFICE

VERNON MURKA, OF DAYTON, OHIO

CRUTCH

Application filed October 1, 1931. Serial No. 566,232.

This invention relates to improvements in crutches.

It is among the objects of the present invention to provide an adjustable crutch of simple design and sturdy structure.

Another object is to provide a crutch which may easily be adjusted lengthwise without the use of special tools.

Further objects and advantages of the present invention will be apparent from the following description, reference being had to the accompanying drawing wherein a preferred embodiment of one form of the present invention is clearly shown.

In the drawing:

Fig. 1 shows a crutch equipped with the present invention.

Fig. 2 is a fragmentary edge view of the lower portion of the crutch to which the invention is applied.

Fig. 3 is a sectional view taken along the line 3—3 of Fig. 2.

Fig. 4 is a detail sectional view taken along the line 4—4 of Fig. 3.

Referring to the drawing the crutch is shown comprising strut members 20 and 21 provided with a shoulder rest 22 and a hand grip 23 which secure the struts together in proper spaced relation.

The lower ends of the struts 20 and 21, or more specifically, the ends opposite the shoulder rest 22 are fitted into a sleeve 24 which holds these ends of the struts properly spaced and also reinforces said struts.

Within the space defined by the inner, adjacent surfaces of the struts and the side walls of the sleeve 24 a leg 25 is slidably supported. The struts prevent wobbly movements of the leg toward the front or back edges of the crutch while the sleeve prevents such movements transversely of the crutch.

As shown in Figs. 3 and 4, the inner surface of the strut 20 is provided with a recess 26 within the confines of sleeve 24. Two openings 27 and 28 extend through said strut from the recess 26 to the outer edge of the strut.

A plate 29 is housed within the recess 26 of strut 20. Fig. 3 shows this plate provided with saw tooth shaped ridges 30.

These ridges each have a surface 31 substan-

tially at right angles to the plate and a sloping surface 32. For purposes to be described, the surface 31 of each ridge is at the bottom as considered in connection with the crutch. The thickness of the plate 29 from the apex of the ridges to the surface adjacent the strut 20 is less than the depth of recess 26 so that when the plate 29 engages the bottom of the recess 26 the sharp edges of ridges 30 will be spaced from the adjacent surface of leg 25.

Plate 29 has projecting lugs 33 and 34 which respectively extend into openings 27 and 28 of strut 20 said lugs preventing movement of the plate longitudinally relatively to the strut, still permitting said plate to be moved transversely of the strut toward the leg 25.

The surface of the sleeve 24, fitting over the surface of strut 20 having openings 27 and 28, has two box-like extensions 35 and 36 respectively aligned with openings 27 and 28. Nuts 37 and 38 are secured within the respective extensions 35 and 36 in any suitable manner so that the nuts may not rotate relatively to the sleeve. Openings are provided in the extensions 35 and 36 to align with the threaded openings of the respective nuts. These nuts receive screws 39 and 40 respectively, each screw being provided with a suitable head which may easily be gripped to permit operation by hand.

From the above description of the device it may readily be seen that while screws 39 and 40 are in the position as shown in Fig. 3, teeth 30 of plate will not grippingly engage the leg 25 and thus this leg may be slid longitudinally of the struts 20 and 21 into any position of adjustment so that the crutch will be of a proper length for the stature of the person to use it. To secure the leg in this position screws 39 and 40 are turned in the nuts 37 and 38 respectively, so that they will exert pressure upon the lugs 33 and 34 respectively thereby urging the plate 29 toward the leg 25 whereby the teeth 30 on said plate will bite into said leg and clamp or lock it in this adjusted position.

Teeth 30 being saw-tooth shaped and arranged so that the right angled surface 31 of each is the

bottom of each tooth, will tend more intimately to grip the leg in response to pressure being exerted upon said leg. However, when screws 39 and 40 are released or turned outwardly in the nuts 37 and 38 and move away from the respective lugs 27 and 28, and the plate 29 with its teeth 30 tends to adhere to the leg 25, a pull on said leg, to move the leg outwardly relative to the struts, will cause the sloping surfaces 32 of the teeth 30 to cam said plate toward the strut 20 and out of engagement with the leg thereby permitting the leg to be slid into the desired adjustment in either direction.

15 In the present invention applicant has provided a crutch of simple structure and design which may conveniently be adjusted for use by various sized persons without necessitating tools of any kind. The device is of 20 such a character that the leg may be locked in any adjusted position, be the adjustments minute or of an extensive character.

While the form of embodiment of the present invention as herein disclosed, constitutes 25 a preferred form, it is to be understood that other forms might be adopted, all coming within the scope of the claims which follow.

What is claimed is as follows:

1. A crutch having two struts held in 30 spaced relation by a shoulder rest at one end and a hand grip intermediate the ends thereof comprising, in combination; a sleeve about the ends of the struts opposite the shoulder rest, holding the struts in spaced relation; a leg 35 slidably supported between the strut ends within the sleeve; a toothed member movably supported in one of said struts; and means supported solely by the sleeve and adapted to be operated to urge the toothed member 40 into gripping engagement with the leg to lock it against movement relatively to the struts.

2. A crutch comprising two strut members held in spaced relation by a shoulder rest and 45 a hand grip one of said members having a transverse opening; a sleeve around the struts holding them in proper spaced relation at the ends opposite the shoulder rest; a leg 50 slidably carried between the strut ends in said sleeve; a toothed member on one of the struts, said member having a pin extending into the transverse opening in the strut to permit only transverse movement of the toothed member relatively to said strut; and 55 means supported by the sleeve and operable to engage the pin of the toothed member to urge said member into gripping engagement with the leg.

60 3. A crutch having two struts secured together in properly spaced relation by a shoulder rest at one end and a hand grip intermediate the ends of the struts, one of said struts having a recess; a sleeve fitting about the ends of the struts opposite the shoulder rest, said sleeve reenforcing the struts and

holding their end portions in proper spaced relation; a leg slidably supported between the strut ends within the sleeve; a plate in the recess in the side of a strut adjacent the leg; sharp edge teeth provided in the surface of the plate adjacent the leg; a pin extending from the opposite side of the plate into the recess provided in the strut; and a member 70 threadedly supported by the sleeve and extending into said recess of the strut and engageable with the pin of the plate to urge said plate toward the leg so that its teeth gripingly engage the leg to lock it against movement.

4. A crutch having two struts a shoulder 80 piece and a hand grip; a sleeve about the lower ends of the struts to brace them and hold them in properly spaced relation; a leg slidably carried between said ends of the struts; a plate interposed between one strut and the leg, said plate having saw-tooth shaped ridges in its surface adjacent the leg; means on the plate for preventing longitudinal movement thereof relatively to the strut; and means carried solely by the sleeve 85 and adapted to be operated to engage the plate and urge it into gripping engagement with the leg to prevent its movement relatively to the struts.

5. A crutch having two struts a shoulder 90 piece and a hand grip, one of said struts having a recess; a sleeve about the lower ends of the struts to brace them and hold them in properly spaced relation; a leg slidably carried between said ends of the struts; a plate interposed between one strut and the leg, said plate having saw-tooth shaped ridges in its surface adjacent the leg; each ridge having a surface at right angles to the plate and a sloping surface, the ridges being 95 so arranged that the right angle surface of each is at the bottom, relatively to the crutch; a threaded nut non-rotatably secured to the sleeve; and a screw in said nut, extending into the recess in the strut and engaging the plate, said screw being adapted to be 100 operated to urge the plate toward the leg so that the teeth gripingly engage the leg to prevent relative movement thereof.

6. A crutch having two struts one of 110 which is provided with an opening, a shoulder piece and a hand grip; a sleeve about the lower ends of the struts to brace them and hold them in properly spaced relation; a leg slidably carried between said ends of the struts; a plate interposed between one strut and the leg, said plate having saw-tooth shaped ridges in its surface adjacent the leg; the angular surfaces of said ridges sloping downwardly toward the leg; a box-like extension in the surface of the sleeve engaging an edge of a strut; a nut secured in said extension of the sleeve; a screw in said nut, extending into the opening in the strut; a pin on the plate, extending into the 115 120 125 130

opening in the strut and engaged by the screw.

7. A crutch having two struts, one of which has a recess in one of its surfaces, and a plurality of openings a shoulder rest and a hand grip in combination with a sleeve about the lower end portions of the struts holding them in predetermined, spaced relation; a leg slidably supported between the said end portions of the struts; a plate in the recess in a strut surface adjacent the leg the thickness of the plate being less than the depth of said recess; downwardly extending, saw-tooth shaped teeth on said plate adjacent the leg; pins on the plate extending into openings in the strut; nuts fitting and secured within depressions in the edge wall of the sleeve said depressions corresponding in shape to the nuts; and screws extending through openings in the sleeve and threadedly engaging the nuts said screws engaging the pins on the plate and being adapted to urge the pins and plate toward the leg whereby the teeth on the plate will bite into said leg and lock it against movement relatively to the struts.

8. A crutch having two struts secured together in spaced relation at one end by a shoulder rest; means surrounding the other ends of the struts and holding them properly spaced; a leg slidably supported between these latter ends of the struts; gripping means interposed between the leg and one strut member; and means supported solely by the surrounding means and engaging the gripping means to urge it into gripping engagement with the leg.

In testimony whereof I hereto affix my signature.
